UNITED STATES PATENT OFFICE.

JOHN F. FALLON, OF ST. LOUIS, MISSOURI.

CARRIAGE-DOOR.

SPECIFICATION forming part of Letters Patent No. 372,847, dated November 8, 1887.

Application filed February 18, 1887. Serial No. 228,035. (No model.)

To all whom it may concern:

Be it known that I, JOHN F. FALLON, a citizen of the United States, residing at the city of St. Louis, State of Missouri, have invented a certain new and useful Improvement in Brougham and other Carriage Doors, of which the following is a full, clear, and exact description.

My invention relates to an improvement on the ordinary system of hanging the doors of broughams, physicians' coupés, and other carriages, and has for its object to avoid the injury to the doors as at present occasioned when swung open, and to enable the doors to be partially or entirely opened while the carriage is in motion.

It consists in sliding the doors backward along and parallel with the outsides of the carriage in lieu of bringing them to the latter, as at present.

On the accompanying drawings, Figure 1 is a side elevation representing a portion of a brougham with door arranged according to my invention; Figs. 2 and 3, plans, respectively, of the upper and lower guide-bars, between which the door is carried, as shown in Fig. 1; and Figs. 4, 5, and 6, full size sections on lines 1 1, 2 2, and 3 3, respectively, on Fig. 1, looking toward the door.

Like letters of reference denote like parts in all the figures.

A represents the side of a brougham partly broken away, and B the door, which is mounted between and carried by the upper and lower guide-bars, C C'. To the front edge of the door B, at its upper front corner, is fixed an iron plate, d, (see Fig. 4,) from the upper end of which projects upward above the door B a guide-piece, e, which takes into a curved groove, f, formed in the under side of the upper guide-bar, C, and extending backward along the latter to near the rear door-pillar, g.

To the inner frame-work of the door B, at the upper rear corner of the latter, is attached a plate, h, from the upper end of which projects upward above the door B a hook or hanger, i, (see Fig. 5,) which, when the door B is in its closed position, as shown in Fig. 1 and by shaded dotted lines in Fig. 2, is away from and out of engagement with a curved guide groove or recess, j, which is formed in the under side of the rear portion of the upper guide-bar, C, and partially closed

transversely at its mouth by an underlapping flat iron bar, k, which is secured to the upper guide-bar, C, and constitutes an internal ledge 55 to the groove or recess j, as hereinafter more particularly referred to. If desired, I may use rollers at the upper end of the plate h in lieu of the hook i.

Along the bottom edge of the door B, at its front corner, is attached a plate, l, from the outer edge of which projects downward a guide-piece, m, which sets in a curved groove, n, formed in the upper side of the lower guide-bar, C', and extending the entire length of the 65 latter to near the door-pillar g.

The door B being in the closed position, as seen in Figs. 1, 2, and 3, with its top and bottom front corner guide pieces, e and m, in their respective grooves f and n, and it being desired to open the door B, its rear portion is pushed or pulled outward until the hook or hanger i at the top is in line with the near end of the groove or recess j of the upper guide-bar, C, and catch onto the ledge k therein, as 70 in Fig. 5, when the door B is thrown back over and parallel with the rear portion of the side A of the carriage into the open position, as indicated by dotted lines to the left of the door B, its front upper and lower guide-pieces, e 75 and m, meanwhile sliding and remaining in their respective grooves f and n, and the rear hook or hanger, i, sliding along the top ledge, k, by which the door B is supported at its rear portion when being opened. On being slid 80 forward for closing, the door B, on arriving opposite to the doorway, is pushed or pulled inward at its rear portion into the closed position, as before, and the hook or hanger i will be again clear of its groove j, sufficient play 85 being allowed to the guide-pieces e and m in their respective grooves f and n to allow at such times for the slight vibratory movement thereon of the door B.

Through the wall of the groove or recess j 90 of the upper guide-bar, C, is left a gap, o, for allowing the hook or hanger i to pass freely to and from the closed position of the door B, out of and into line with the groove j.

By my invention the opening of the door B 100 can be regulated at pleasure while the carriage is in motion without causing obstruction or accident, and the carriage can be coupled shorter, as there is no danger of the door foul-

ing the wheels or striking tree-boxes, hitch-posts, stepping-stones, or other obstructions, as is the case when the doors are swung open on their hinges.

5 I claim as my invention—

In a brougham or other carriage, the door B, having guide-pieces e m and hook or hanger i, in combination with upper guide-supporting bar, C, having grooves f j and ledge k, and lower guide-supporting bar, C', formed with

groove n, substantially as shown, and for the purpose described.

In testimony whereof I affix my signature, in presence of two witnesses, this 23d day of December, 1886.

JOHN F. FALLON.

Witnesses:

S. L. SCHRADER,

EDWIN SAUTER.
